DIRECTION SELECTION CONDENSER

John J. Root, New York, N. Y.

Application October 22, 1949, Serial No. 123,021

6 Claims. (Cl. 175—41.5)

1

This invention relates to direction selection condensers such as may be used in television antenna systems although they may be employed in other circumstances. The instant application is a continuation in part of my prior application Serial No. 72,700, filed January 25, 1949, now abandoned.

In the above mentioned prior application, it was pointed out that television stations are generally dispersed in various directions relative to most television receivers. If a receiver is located in a central district, the receivable transmitting stations may be disposed in virtually all directions around the receiver. Television receivers conventionally require antenna which are highly directional and which therefore require rotation or orientation in order to satisfactorily receive any particular transmission. It is difficult to physically orient the antenna for each station that is tuned in, and in general, compromises are practiced by permanently orienting the antenna in the general direction of the most desired stations. Antennas are often installed directly within or adjacent the receiver cabinet so that physical orientation then becomes practical. However, this method limits the size of the antenna elements and often involves undue production and installation expenses.

In my prior application, I described the provision of crossed directional elements which were electrically connected to a four-part rotary condenser.

According to the present invention, the condenser is constructed substantially without bolts or any fastening devices while the required capacity and operating precision is nevertheless maintained. The condenser further has a high efficiency in that some of its plates are coated with a substance of low dielectric characteristics.

The condenser, as constructed herein, offers further manufacturing economies and installation conveniences, as will hereinafter be made clear.

Referring to the drawings:

Fig. 1 is a side elevational view of the complete rotary condenser of the instant invention.

Fig. 2 is a front end view thereof in elevation.

Fig. 3 is a rear end view thereof.

Fig. 4 is a side elevational view before the stator plates are applied.

Fig. 5 is an enlarged cross-sectional view as taken along the lines 5—5 of Fig. 2.

Fig. 6 is a developed view of a stator plate.

Fig. 7 is a developed view of the spring terminal lug for the rotor plates.

2

Fig. 8 is a view taken substantially along the lines 8—8 of Fig. 5.

Fig. 9 is a cross-sectional view taken substantially along the lines 9—9 of Fig. 5; and

Fig. 10 is a cross-sectional view taken substantially along the lines 10—10 of Fig. 5.

The condenser comprises the four equi-spaced arcuate stator plates or segments 15, 16, 17 and 18 disposed edge to edge in a circle and insulated from each other. Such disposition is maintained by the insulating disks 19 and 20 to which the stator plates are physically connected. The device is employed by connecting each of the crossed directional antenna elements to opposite stator plates so that each pair of opposing stator plates represents a particular direction. Rotor plates 21 and 22, when rotated, provide condenser action with opposite stator plate sections so as to effectively select any particular direction within 360 degrees as will hereinafter be made clear.

The construction and assembly of the condenser may best be understood from the cross-sectional view of Fig. 5. An elongated, insulating shaft 23 is flattened along portion 24 of its periphery in order to maintain the rotor plates in position. The rotor plates are formed with depending arms 25 having opening 26. Openings 26 are generally round but have a flattened portion in order to conform to the cross-sectional shape of shaft 23.

Many methods may be employed in assembling the instant article but a practical method is as follows: Shaft 23 is first inserted through an opening 26 of depending arm 25 of plate 22 and an insulating spacer 27 is then applied over the shaft. Thereafter, the shaft is passed through the depending arm opening of rotor plate 21. An insulating tube 28 is then placed within the rotor plates and slipped over shaft 23. Thereafter, shaft 23 is passed through the opposite depending arm opening of plate 22, another insulating spacer 29 is applied, and depending arm opening of plate 21. By these steps, the rotor plates are correctly mounted on the shaft in diametrically spaced relationship and are suitably insulated from each other. In order to maintain such relationship, a pin 30 is passed through tube 28 and shaft 23 so as to prevent disassembly of the parts.

A pair of spring lugs 31 and 32 are now inserted over shaft 23 on both sides of the rotor plate assembly. The spring lugs not only serve as fixed terminal means for the rotating rotor assembly but serve as stabilizers for its operation. They are formed of a resilient metal and may be silver-plated or the like to increase con-

ductivity. As shown in Fig. 7, the spring lug is formed of a base section 33 and an arm 34 which is bent along line 35 so that the spring lug becomes essentially L-shaped in form. Base section 33 is somewhat triangular in shape so as to form spring fingers 36. Such spring fingers are bent upwardly as illustrated in Figs. 4 and 5 so as to provide the required spring action.

After application of the spring lugs on both ends of the rotor assembly, insulating spacers 37 and 38 are positioned at each end of the shaft. Thereafter, the insulating disks 19 and 20 are placed in position at the respective ends of the shaft.

The insulating disks 19 and 20 are formed with a plurality of openings 40 around the edges thereof. Each arm 34 of the spring lugs 31 and 32 is passed through one of said openings as illustrated in Figs. 2, 3 and 5. Disk 19 is provided with a central annular, brass collar 42 which fits over the shaft 23. In the same manner, disk 20 is provided with a brass collar 43 having a threaded end 44 which may serve to receive a nut as when the device is to be secured to a cabinet wall.

In order to maintain the assembly of the disks and other components as heretofore described, the four stator plates 15, 16, 17 and 18 are now applied over the rotor plates and so as to jointly grasp and secure the disks. Referring to Fig. 6, which is a developed view of a stator plate, it will be observed that the plate is cut along line 45 so as to provide a projection or lug 46. The other end is cut along line 47 so as to provide a projection or lug 48 and an electrical connection lug 49. The stator plate is then rendered concavo-convex in form as by any suitable die. Projections 46 and 48 are bent inwardly so that such lugs are made available for connection to the disks while the lug 49 is employed for electrical connection to the antenna elements. In order to connect the stator plates in position, projection 46 is inserted in a bottom opening 40 of disk 19 as illustrated in Fig. 3 while the top projection 48 is snapped into an opening 40 of disk 20. All four stator plates are thus applied, the end result being the formation of the complete rotary condenser as illustrated in Figs. 1 and 5. It will be observed from the foregoing that substantially no screws or bolts were required in assembling the article, such assembly being effected by the stator plates and being rendered stable and precise through the spring action of the lugs 31 and 32.

In order to improve the operating characteristics of the condenser over a wide range of frequencies, I determined that the dielectric factor between the condenser plates should be decreased in order to eliminate sharp or peak tuning at particular points so as to widen the response curve. This expedient is very useful in that the condenser is intended to operate over a wide band of frequencies, and sharp tuning at any particular points should be avoided. To this end, I have applied a thin coating of graphite 55 to the periphery of the rotor plates. As a result of such coating, stability and uniformity of operation over the wide band of frequencies required is accomplished.

Briefly, the rotary condenser is employed as follows:

A pair of dipoles are disposed in crossed relationship so as to form four inner terminal ends approximately 90 degrees apart. Each terminal end is then connected to a respective lug 49 of each stator plate. Accordingly, each stator plate

represents one dipole section. Connections are then made from arms 34 to the input terminals of the television receiver. It will be recognized therefore that rotation of shaft 23 will rotate the rotor plates 21 and 22 so as to capacitatively derive antenna voltages from any particular quadrant of the composite directional antenna elements. Thus, the rotation of shaft 23 is equivalent to physically rotating a directional antenna.

The rotary condenser of the instant invention may be employed with an outside antenna or with one that is mounted within or adjacent to the television receiver cabinet. Inasmuch as physical rotation of the antenna is eliminated, it may be disposed in ordinarily inaccessible places and may be made of larger elements than would be practical or possible, if it was to be physically rotated.

What is claimed is:

1. A rotary condenser comprising a plurality of arcuate stator plates edge-to-edge disposed in a circle and insulated from each other, a pair of insulating disks at the respective ends of said stator plates, said disks being formed with openings therethrough, integral snap lugs formed on each stator plate and received into said disk openings so as to effect a physical connection between said stator plates and disks for maintaining said stator plates in their circular disposition, a rotatable shaft, and a pair of rotor plates mounted on said shaft so as to be adjacent and rotatable relative to said stator plates for condenser action with selectable ones of said stator plates.

2. A rotary condenser comprising a plurality of arcuate stator plates edge-to-edge disposed in a circle and insulated from each other, a pair of insulating disks at the respective ends of said stator plates, said disks being formed with openings therethrough, integral snap lugs formed on each stator plate and received into said disk openings so as to effect a physical connection between said stator plates and disks for maintaining said stator plates in their circular disposition, a pair of rotor plates mounted within said stator plates for condenser action with selectable ones of said stator plates, a shaft extending through said disks and upon which said rotor plates are mounted, and a pair of spring lugs mounted on such shaft, each spring lug having a spring portion thereof disposed between one of said rotor plates and one of said disks so as to bear against said rotor plate and disk respectively with a spring force, each of said spring lugs further including a projection extending through the disk against which it bears, said projection serving as an electrical terminal for the rotor plate against which the spring lug bears.

3. A rotary condenser comprising a plurality of arcuate stator plates edge-to-edge disposed in a circle and insulated from each other, a pair of insulating disks at the respective ends of said stator plates, said disks being formed with openings therethrough, integral snap lugs formed on each stator plate and received into said disk openings so as to effect a physical connection between said stator plates and disks for maintaining said stator plates in their circular disposition, a pair of rotor plates mounted within said stator plates for condenser action with selectable ones of said stator plates, a shaft extending through said disks and upon which said rotor plates are mounted, and a pair of spring lugs mounted on such shaft, each spring lug having a spring por-

5

tion thereof disposed between one of said rotor plates and one of said disks so as to bear against said rotor plate and disk respectively with a spring force, each of said spring lugs further including a projection extending through the disk against which it bears, said projection serving as an electrical terminal for the rotor plate against which the spring lug bears, each of said rotor plates having an outer coating of graphite.

4. A rotary condenser comprising a plurality of arcuate stator plates edge-to-edge disposed and insulated from each other, a pair of insulating disks each connected at the respective ends of the stator plates and supporting said plates, a pair of rotor plates mounted for condenser action with selectable ones of said stator plates and spring lugs effecting contact with said rotor plates and extending through said disks so as to serve as terminals for said rotor plates, each of said spring lugs comprising a base having a spring member thereon, one terminal of said spring member abutting against one of said rotor plates and the other terminal abutting against one of said disks so as to effect a secure mechanical assembly between the disks and the stator plates while providing an electrical connection to the rotor plates.

5. A rotary condenser according to claim 4 and wherein each of said disks is formed with a plurality of openings therethrough, and an offset integral member on each of said stator plates

20
25

entering into, so as to be engaged by, said openings in said disks.

6. A rotary condenser comprising a plurality of arcuate stator plates edge-to-edge disposed and insulated from each other, a pair of insulating disks connected at the respective ends of the stator plates, a pair of rotor plates mounted for condenser action with selectable ones of said stator plates and spring lugs effecting contact 5 with said rotor plates and extending through said disks so as to serve as terminals for said rotor plates, each of said rotor plates having end depending arms formed with an opening therethrough, and a shaft extending through each of 10 said depending arm openings and through said disks, each of said disks being formed with a plurality of edge openings therethrough and an offset integral member on each of said stator plates snapped into said openings of said disks. 15
